CLAIM

The ornamental design for a cultivator tine, substantially as shown.

DESCRIPTION

FIG. 1 is a side elevational view of a cultivator tine embodying our new design.

FIG. 2 is a side elevational view looking in the direction of arrow II in FIG. 1.

FIG. 3 is a perspective view thereof.

FIG. 4 is a top plan view thereof looking in the direction of arrow IV in FIG. 2, and

FIG. 5 is a bottom plan view thereof looking in the direction of arrow V in FIG. 2.
